UNITED STATES PATENT OFFICE.

GEORGE B. GALLUP, OF BRADENTON, FLORIDA, ASSIGNOR TO LEACH-GALLUP MANUFACTURING COMPANY, OF BRADENTON, FLORIDA, A CORPORATION OF FLORIDA.

ELECTRIC HEATER.

Application filed May 3, 1928. Serial No. 274,881.

This invention relates to electric heaters and has for one of its objects to provide a heater of this character which will be simple in construction, comparatively inexpensive to manufacture and more efficient in use than those which have been heretofore proposed.

A further object of the invention is to provide an electric resistance heater in which one or more heat-conducting and radiating rings or members are arranged in proximity to the electric resistance element whereby heat from the latter is transmitted to such rings or members which in turn serve to heat the air surrounding them whereby the efficiency of the heater is greatly increased.

With the above and other objects in view which will appear as the description proceeds the invention consists of the novel details of construction and combinations of parts more fully hereinafter disclosed and particularly pointed out in the appended claims.

Referring to the accompanying drawings forming a part of this specification in which like reference characters designate like parts in all views:

Fig. 1 is a perspective view of a heater constructed in accordance with the present invention.

Fig. 2 is a central vertical sectional view taken approximately on the plane indicated by the line II, II of Fig. 3.

Fig. 3 is a front elevational view of the heater, and

Fig. 4 is a view similar to Fig. 3, but with the outer cover plate or grid removed.

Referring more particularly to the said drawings the numeral 5 indicates a suitable casing preferably formed of stamped sheet metal which may be cylindrical or in other desired shape in cross section, having a rear wall 6, in the approximate center of which is mounted an electric socket or receptacle 7, of the ordinary screw base type. As clearly shown in Fig. 2 the said socket 7 projects through the rear wall 6 and the base 8 thereof receives the electrical conductors 9 through which electric current is supplied to the device. A cover member 10 is secured to the rear wall 6 as by the bolts 11 and houses the rear portion of the socket 7, the rear wall 12 of said cover member being provided with a suitable opening 13 in which is fitted an insulating bushing 14 through which passes a cable 15 which carries the conductors 9. The socket 7 receives an electrical resistance or heating

element of well-known form which comprises a porcelain or other suitable refractory support 16 upon which is mounted a spiral resistance wire 17 which is connected in the electrical circuit in the well-known manner. 60

Extending through the rear wall 6 of the casing 5 is a plurality of studs or bolts 18 upon which is mounted one or more heat-conducting and radiating members 19. The said members 19 may be cast or stamped by means of suitable dies to provide a central solid portion 20 having a central opening 21 to accommodate the resistance element and from the said central portion 20 a plurality of arms or spokes 22 radiate to an outer rim or 70 ring 23, as clearly shown in Figs. 2 and 4. The central portion 20 of each member 19 is provided with a plurality of lugs or projections 25 by means of which the said members 19 are maintained in spaced relation, as will 75 be readily understood from Fig. 2. Nuts 26, threaded upon the studs or bolts 18, retain the rings or members 19 in operative positions.

The left hand edge of the casing 5, as viewed in Fig. 2, is provided with an outwardly turned flange 28 to which is secured, as by the bolts 29, a cover member 30. This member, like the members 19, may be stamped or cast, being provided with suitable perforations 31, through which air may circulate in 80 the well known manner.

The device is adapted for use either as a stationary or as a portable heater and when intended as the latter it may be provided with a suitable base 32 and a handle 33 by means 90 of which latter it may be carried from place to place. When designed for use as a stationary heater the base and handle may be omitted and suitable lugs provided whereby it may be attached to studding or other portion of the wall within a suitable recess provided in such wall.

The apertures 21 formed in the heat-conducting members 19 are preferably of only slightly larger diameter than that of the electric resistance element so that there is only a small air space between the element 17 and the inner portions of the members 19, whereby heat from the resistance element may be readily transmitted to the metallic radiating members 19. 100

These members are thus readily heated and owing to their extensive surface serve to more effectively transmit heat to the air which circulates throughout the heater in the well- 105 110

known manner. Heat will also be transmitted to the members 19 through the bolts or studs 18 as well as by radiation to the casing 5 from which it will be reflected in the manner of the ordinary heater of this type.

While one form of the invention has been illustrated and described, it is obvious that those skilled in the art may vary the details of construction as well as the precise arrangement of parts without departing from the spirit of the invention and therefore it is not wished to be limited to the above disclosure except as may be required by the claims.

What is claimed is:

15. 1. In an electric heater, a casing; an electrical heating element mounted in said casing; and heat conducting and dissipating means comprising a perforated metallic plate mounted in said casing concentric with said element and in close proximity thereto, adapted to readily transmit heat from said element to the surrounding atmosphere.
20. 2. In an electric heater, a casing; an electrical heating element mounted in said casing; and a plurality of axially spaced perforated heat conducting plates mounted in said

casing concentric with said heating element and in close proximity thereto, adapted to readily transmit heat from said element to the surrounding atmosphere.

30

3. In an electric heater, a casing; an electrical heating element mounted in said casing; a plurality of axially spaced perforated metallic plates mounted in said casing concentric with said element and in close proximity thereto, adapted to readily transmit heat from said element to the surrounding atmosphere; and a perforated cover and guard plate secured to said casing in front of said heating element.

35

4. In an electric heater, a casing; an electrical heating element mounted in said casing; a plurality of axially extending studs carried by said casing around said heating element; and a plurality of perforated heat conducting and dissipating plates mounted on said studs, said plates being provided with lugs for maintaining adjacent plates in axially spaced relation.

40

In testimony whereof I affix my signature,

GEORGE B. GALLUP.
